UNITED STATES PATENT OFFICE.

JONATHAN P. B. FISKE, OF NEWTON, MASSACHUSETTS, ASSIGNOR TO FISKE & COMPANY, INC., A CORPORATION OF MASSACHUSETTS.

WALL CONSTRUCTION AND RIBBED CHANNEL-BRICK THEREFOR.

1,250,295.

Specification of Letters Patent.

Patented Dec. 18, 1917.

Application filed March 20, 1914. Serial No. 826,098.

To all whom it may concern:

Be it known that I, JONATHAN P. B. FISKE, a citizen of the United States, and resident of Newton, county of Middlesex, 5 State of Massachusetts, have invented an Improvement in Wall Construction and Ribbed Channel-Brick Therefor, of which the following description, in connection with the accompanying drawings, is a specification, like letters on the drawings representing like parts.

My present invention is a novel form of wall construction employing a novel type of channel ribbed tile or block. In the manufacture of hollow tile for building construction, great difficulty has heretofore been experienced in making such a wall moisture-proof, as the moisture was apt to work through the horizontal courses of mortar. 15 I have discovered that, by forming a ribbed channel brick with projecting ribs of very substantial length and on opposite sides of the body portion, a moisture-proof wall could be constructed. Preferably also I arrange such a channel brick with such ribs to obtain the benefit of an interlocking or overlapping ribbed construction, and prefer to form said interlocking ribs of substantially equal extent or height, so that each rib will 20 overlap the other for substantially its entire length and constitute a series of load carrying ribs, flanges or webs, and afford a seat for a small course of mortar between the projecting ribs of one channel brick and the web or body portion of the adjacent brick or tile. 25 As herein illustrated in preferred forms, I provide a block or tile with ribs projecting from opposite sides of substantially equal depth and so arranged as to afford a firm 30 solid supporting construction at either surface of the wall. It is a further important object of my present invention to provide a channel brick of simple construction, which may be readily formed in a die machine, 35 with the ribs formed continuously as the brick or tile material is forced out of the die, permitting rapid and economical construction, as will be readily understood by those skilled in this art. Preferably I provide a 40 die to form two of such ribbed tile at once to be subsequently cut longitudinally into two open channel blocks, each adapted to interfit and interlock with the other.

A special feature of a wall constructed of my interlocking channel brick is the very

great strength of such wall, not only in its load-carrying or compressive capacity, but also in its lateral strength. I have discovered that a wall formed of such interlocking brick will withstand very severe 60 lateral strains, even yielding and "springing" laterally and instantly returning to normal form when the lateral strain is removed, without in the least disrupting the wall formation, mortar courses, or strength. 65 In fact, the entire wall, to an appreciable extent, possesses an inherent resiliency heretofore unknown in brick construction. I attribute this result to the "truss" construction, i. e. a large number of interlocking 70 webs and ribs, vertically and horizontally positioned throughout the wall, and tied together by the horizontal body portion built integrally into each of the side walls and with the overlapping rib and mortar connections thereto, thus giving a basket-like 75 strength or tenacity, laterally, diagonally, and in substantially all directions, providing a firm interlacing of the vertically adjacent rows of channel brick.

Other features of the invention, novel details of construction, and advantages, will be hereinafter more fully pointed out and claimed.

Referring to the drawings,

Figure 1 illustrates one form of my improved ribbed building block in cross section, as the same issues from a die, said block being afterward cut in two longitudinally to form two separate blocks;

Fig. 2 is a perspective view, partly in cross section, of a wall construction embodying the form of tiles illustrated in Fig. 1;

Fig. 3 shows in cross section a modified form of ribbed tile, as the same issues from the die of the machine comprising two bricks;

Fig. 4 illustrates a wall construction made from the tile of Fig. 3;

Fig. 5 shows a still further form in cross section of ribbed tile;

Fig. 6 illustrates a wall construction of the tile shown in Fig. 5;

Figs. 7 and 8 show respectively still further modified forms of my ribbed tile as the same is made and as built in a wall.

The channel brick illustrated in Figs. 1 and 2 comprises the web or body portion 1 and the oppositely depending flanges 2, 2, on one side, and the centrally projecting rib 110

3 on the opposite side, each tile being cut longitudinally along the serrated or weakened portion 4 of the stream of tile material, as the same issues from a die in duplex 5 form, as shown in Fig. 1. The tile are cut in proper lengths by any side cutting or rotary wire cutter, and are then built as shown in Fig. 2 in a wall. Preferably the web or body portion 1 is of sufficient width for the 10 entire width of wall construction in which the tile will be used, and the outer faces of the depending flanges 2, 2 may be finished, roughened, or otherwise treated to constitute the exposed surface of the wall. Preferably 15 the central rib 3 and open depending ribs 2, 2, are of equal extent in depth and thickness, and co-extensive in length with the body portion 1, said rib and flanges also being of substantially the same thickness as 20 the body portion 1 of the tile. In building a wall construction, I prefer to lay the mortar strips 5, 6, and 7 as shown, the mortar strips 5, and 6 being of slightly greater width than the thickness of flanges 2, and serving to 25 support and unite the same on to the body portion of the next adjacent hollow tile, while the central rib 3 is also utilized, preferably as an aid to support the wall by the intermediate mortar strip or ribbon 6, as 30 clearly illustrated in Fig. 2. A wall so constructed contains the two horizontal air spaces 8 and 9, and any moisture which may possibly be driven through the mortar strip 7 on one side could not work up over the 35 central rib 3 nor across the two spaces 8 and 9 to the opposite side of the wall. This feature of a moisture-proof construction is of the greatest importance in hollow tile walls, and has heretofore been a serious objection 40 to this type of building construction. By means of my ribbed hollow tile herein illustrated, I provide the rib 3 and spaces 8 and 9 across which moisture, which might penetrate in one side of the wall, cannot be 45 driven, or work clear to the other side of the wall. Furthermore this ribbed tile permits of speedy assembling and construction.

The form or ribbed tile illustrated in Fig. 3 is formed in a similar manner to that already explained, having a horizontal web or body portion 10 with two depending side flanges or faces 11, 11 and centrally projecting ribs 12, 12 on the opposite side to the flanges 11. As illustrated in Fig. 4, this 50 type of hollow tile affords a plurality of horizontal air spaces 13 and 14, each affording a space from the mortar courses 15 and 16 with the central mortar course 17, thus securing the moisture-proof wall. Any 55 moisture which might work through the courses 15 would not be able to work up over the ribs 12 through the intermediate mortar 17 and opposite corresponding rib 12, and across the second air space 13 to the other 60 side of the wall.

In the form illustrated in Figs. 5 and 6, I form the body portion 18 of my hollow tile with the depending side flanges or ribs 19, and oppositely extending ribs 20 so as to secure a central air space 21 in the wall constructed therefrom. In building a wall with this type of tile, I may either form the mortar course 22 as a solid filling between the depending flange 19 of one tile and the adjacent rib 20 of the next tile, so that said 70 mortar will take up part of the load of the wall and thus afford a solid side wall construction, or I may simply form the relatively narrow strip or ribbon of mortar as shown at 23 on the other side of the wall 80 illustrated in Fig. 6, or I may use the solid mortar course 22 on one side and leave an additional air space 24 on the side adjacent the narrow mortar course as is illustrated in Fig. 6. In either case I obtain the advantages of a moisture-proof wall, with the mortar courses spaced apart so that any moisture working in through the course 22, for example, even if it could possibly work up over the relatively high rib 20, could not work 90 across the open air space 21 and over the second rib 20 and out to the other side of the wall.

In Figs. 7 and 8 I have illustrated a still further modified form, wherein the hollow tile comprises a hollow web or body portion 25, having a plurality of projecting ribs on one side, 26, 26, being the usual ribs, and 27, 27 the intermediate ribs, while on the opposite side of the body portion 25 are the 100 oppositely extending ribs 28; preferably each of these ribs are substantially equal in extent, and a duplex hollow tile from which my hollow tile is cut, would be formed as illustrated in Fig. 7, and cut longitudinally 105 into two tiles. These tiles may be built into a wall construction either with the sides having the four projecting ribs downwardly, or upwardly, the latter form being shown in Fig. 8, and in either instance a firm interlocking hollow tile construction is secured, the projecting ribs 28 on one side fitting within an outer rib 26, and middle rib 27 of the reverse side of the adjacent block, as clearly illustrated in Fig. 8, the intervening 110 air space 29 effectually separating the two sides which constitute the inner and outer bearings of the wall. The mortar courses 30 I prefer to form substantially as shown in Fig. 8, giving a firm solid supporting surface utilizing the three adjacent ribs 26, 28, and 27 of each pair of interlocking tiles, and giving a very strong, rigid supporting construction. It will be noted that the mortar courses 30 are of zig-zag or Z-shape, 115 which not only binds together the interlocking ribs and webs of adjacent channel brick, but also holds the same firmly in position and solidifies the entire mass, while presenting a peculiar form of mortar course 120 125 130

through which moisture will not seep or be driven. This zigzag feature is distinctly novel and is of importance in the entire wall construction.

5 In each of the forms herein illustrated of my ribbed hollow tile, the body portion of the block or tile constitutes the horizontal web tying the two sides of the wall rigidly in place, at least one of the ribs on said body 10 portion constituting a part of the side wall construction itself. All these different types secure the advantages of a moisture-proof wall, of an interlocking hollow tile construction, and of a tile and wall which can be 15 quickly, easily and readily built. Furthermore, the tiles herein shown can be used as finishing or top tiles, the projecting ribs 3 in the form shown in Figs. 1 and 2, 12, 20, and 28 respectively in the other forms of the 20 block shown, being simply knocked off and the top of the body portion of each tile presenting a smooth surface to receive joists, timbers, or the like. The oppositely projecting ribs are substantially equal in extent, 25 and each of the same width and strength as the other and an even distribution of weight and strain is carried thereby. All horizontal mortar courses on one side of the wall are absolutely separated from the mortar 30 courses on the other side by vertical partitions on each tile and by an open air space, to attain the highly desirable moisture-proof feature as already explained. The horizontal air passages are intercommunicating 35 through the abutting ends of the adjacent channel brick in each row, by the omission of the vertical mortar course, as clearly indicated at 31, in Fig. 6, so that both horizontal and vertical air passages are provided 40 and the benefit of a complete air circulation is afforded. My novel form of channel ribbed brick enables a hollow wall construction to be laid up with a double pair of wall sides, each side consisting of a pair of 45 load carrying ribs, preferably interlocking, and preferably solidified by the bonding material. Furthermore, a moisture-proof wall construction is provided having horizontal air openings separating the mortar courses, 50 as well as an interlocking feature in each one of the twin walls, which walls inclose one or more central horizontal air spaces. The great advantages of economy of material, lightness of construction for transpor- 55 tation, etc., speed and facility in laying up a wall of such channel brick formation will be fully appreciated, and the pair of twin walls, each wall comprising a plurality of load carrying ribs or webs, and with alter- 60 nate mortar layers constituting a solid fire- resisting construction, is of special value. By having the oppositely projecting ribs or webs substantially equal in width, even burning of this type of channel brick is in- 65 sured, all the webs and ribs being of ap-

proximately equal thickness and thus the material shrinking uniformly during drying and burning. The channel brick of my present application is characterized by the provision of a plurality of parallel ribs or webs on opposite sides thereof, so formed as to enable the twin wall construction above explained to be built, but in my copending application, Serial No. 826,099, filed March 20, 1914, I have claimed the channel brick 70 and the double or twin wall construction formed of interlocking and overlapping flanges extending from one side only of the horizontal portion. In my copending application Serial No. 871,271, filed November 10, 1914, I have shown a further form of simple construction of channel brick, embodying the double or "twin wall" feature common to my said applications, and I have elected to claim the "twin wall" feature 85 broadly in said application.

Having described my invention, what I claim as new and desire to secure by Letters Patent is:

1. A channel brick for hollow wall construction, each brick comprising a central body portion on each side of which are formed twin walled mortar receiving channels, on one surface, and a non-aligned, interlocking lug on the other surface, said channels being of substantial width and all parts of the brick being of substantially equal thickness, whereby pillars of alternating brick and bonding material, with the intervening inner air space are provided in the 100 wall structure.

2. A channel brick for hollow wall construction, each brick comprising a central body portion on each side of which are formed vertically extending ribs constituting twin walled mortar receiving channels on one surface of the body portion, the outer rib being of substantially standard brick area, and a vertically extending interlocking lug on the opposite surface between each pair 105 of ribs, the body portion and said vertically extending ribs and lug being of substantially equal thickness, whereby pillars of alternating brick and bonding material, with the lug on one brick interlocking between the pair 110 of ribs on an adjacent brick, are provided with an intervening air space in the wall structure.

3. A channel brick for hollow wall construction, provided with a body portion and vertically extending ribs or wall sections on one side, a non-aligned rib on the other side, said sections being arranged in spaced pairs adjacent the ends of the body portion, the outer walls of each pair being the wall faces 125 of the brick, and the said spaced pairs providing a substantial open mortar receiving channel of greater width than said non-aligned lug.

4. Hollow wall construction, comprising 130

- 4
- a plurality of super-imposed channel brick, each brick having a body portion with a plurality of vertically extending ribs, said ribs having vertical side walls, and each 5 brick including a spaced pair of ribs adjacent each outer edge of the brick on one side, and a non-alined rib on the opposite side, said outer pairs of ribs constituting mortar-receiving channels, motar uniting 10 each of said outer pairs of ribs into a load-carrying pillar of vertically alternating brick and bonding material, and each load-carrying pillar being adjacent an air space in the wall.
15. 5. Hollow wall construction, comprising a plurality of super-imposed channel bricks, each brick being of a width substantially equal to the thickness of the wall and having a horizontal body portion connecting spaced 20 pairs of perpendicularly extending ribs extending from one side adjacent each wall face and a non-alined rib in the opposite side between each pair, each outer rib of the pairs being of substantially standard 25 brick area, said pairs of ribs constituting mortar receiving channels and having the ribs of each pair united into a load-carrying pillar of alternating brick and mortar material, the inner rib of each pillar being 30 adjacent a horizontal air space in the wall.
6. Hollow wall construction, comprising twin walls united by tie members of brick material adjacent air spaces in the wall, each tie member comprising a body portion 35 extending from wall to wall and having a plurality of vertically extending ribs in each wall, spaced pairs of ribs on one side and a non-alined rib on the opposite side, all said ribs in each wall having vertical sides and being united by mortar into a load-carrying 40 pillar of vertically alternating brick and bonding material.
7. Hollow wall construction, comprising twin walls united by tie members of brick material adjacent air spaces in the wall, 45 each tie member comprising a body portion extending from wall to wall and having a plurality of vertically extending ribs in each wall, spaced pairs of ribs on one side and a rib on the opposite side, between each pair, 50 all said ribs in each wall having vertical sides and being united by mortar into a load-carrying pillar of vertically alternating brick and bonding material.
8. In a building brick of the class de- 55 scribed a top plate or body portion provided on its upper face at each side thereof with a pair of spaced apart upstanding webs or ribs the outer webs constituting the sides or exposed faces of the brick and forming 60 with the adjacent webs a pair of continuous spaced apart mortar channels, and on its lower face with the depending webs or ribs non-alined with the top side ribs coöperating therewith to form zig-zag mortar courses 65 interrupted by a central air-space through-out the wall.
- In testimony whereof, I have signed my name to this specification, in the presence of two subscribing witnesses.
